UNITED STATES PATENT OFFICE

LEWIS C. PACKER, OF LONGMEADOW, AND RALPH E. KRUCK, OF SPRINGFIELD, MASSACHUSETTS, ASSIGNORS TO WESTINGHOUSE ELECTRIC AND MANUFACTURING COMPANY, A CORPORATION OF PENNSYLVANIA

DESIGN FOR A VACUUM CLEANER

Application filed February 1, 1933. Serial No. 47,079. Term of patent 7 years.

To all whom it may concern:

Be it known that we, LEWIS C. PACKER and RALPH E. KRUCK, citizens of the United States, residing respectively, at Longmeadow, in the county of Hampden and State of Massachusetts; and Springfield, in the county of Hampden and State of Massachusetts, have invented a new, original, and ornamental Design for Vacuum Cleaners, of which the following is a specification, reference being had to the accompanying drawing, constituting a part hereof.

Figure 1 is a top plan view of a vacuum cleaner showing our new design;

Fig. 2 is a view, in front elevation thereof, and

Fig. 3 is a view, in side elevation thereof.

We claim:

The ornamental design for a vacuum cleaner substantially as shown.

In testimony whereof, we have hereunto subscribed our names this 27th day of January, 1933.

LEWIS C. PACKER.
RALPH E. KRUCK.
